(57) **CLAIM**

The ornamental design for a USB drive having MP3 function, as shown and described.

DESCRIPTION

FIG. 1 is a front, right perspective view of the USB drive having MP3 function showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top reference view of the USB drive having MP3 function shown without its top cover.
